UNITED STATES PATENT OFFICE.

VINCENT GAGE, OF WASHINGTON, DISTRICT OF COLUMBIA.

PAPER GUIDE FOR TYPEWRITING MACHINES.

Application filed July 3, 1926. Serial No. 120,440.

In the operation of a typewriting machine to make duplicate copies, as in manifolding, the sheets of paper and the carbon inserts frequently become disarranged or are car-

5 ried around the platen a second time, resulting in defective work and occasioning loss of time and the waste of paper which in the aggregate is an item of no small importance, particularly in cases where man-

10 ifold copies are required in a limited time.

This invention provides an attachment for use in conjunction with the usual platen and paper table or shelf of a typewriter, which may be easily placed in position and which

15 will guide the paper and carbon inserts to the platen and prevent disarrangement thereof, or a winding of the same or any part thereof about the platen a second time, said attachment being adjustable along the

20 length of the platen to any desired position according to the nature of the work or the width of the paper.

The invention furthermore contemplates the provision of an attachment of the nature 25 aforesaid, which when applied to the typewriting machine may remain in place regardless of the particular nature of the work to be performed, as it may be shifted so as not to interfere with the general use of the 30 machine.

The invention also supplies an attachment for the purpose stated which may be cheaply manufactured and marketed at a small cost and which is light, effective and adapted to 35 be placed in position by the average operator.

While the drawings illustrate a preferred embodiment of the invention it is to be understood that in adapting the means to meet 40 specific needs and requirements, the design may be varied and such other changes in the minor details of construction may be resorted to within the scope of the invention as claimed, without departing from the 45 spirit thereof.

For a full understanding of the invention and the merits thereof, reference is to be had to the following description and the drawings hereto attached in which,—

50 Figure 1 is a top plan view of a typewriting machine provided with a paper guide embodying the invention.

Figure 2 is a detail sectional view on the line 2—2 of Figure 1, looking to the left, 55 as designated by the arrows, showing the parts on a larger scale.

Figure 3 is a detail perspective view of the paper guide, and

Figure 4 is a view similar to Figure 3, of a modification.

Corresponding and like parts are referred to in the following description and designated in the several views of the drawings by like reference characters.

The typewriting machine shown is of the 65 variety in which the carriage includes a platen 1, a shelf or table 2 for the paper and a rod 3 forming supporting means for the pressure rolls 4 which hold the paper to the platen 1.

The paper guide comprises a member 5 which, in the preferable construction consists of a strip of spring metal having a clasp 6 at one end to engage the rod 3 and having its opposite end portion recurved to form a rest 7 which engages the upper edge portion of the paper shelf or table 2, as indicated most clearly in Figure 2. In this manner the paper guide is properly positioned and the upper end is free from projecting 80 edges which would be liable to catch the paper and interfere with its proper movement. As indicated most clearly in Figure 1, usually two of the paper guides are applied to a machine, so as to properly support 85 opposite edge portions of the paper. These guides are freely movable along the rod 3 and paper shelf 2, hence may be adjusted to any desired position according to the width of the paper or to be out of the way, 90 without necessitating the removal of the guide from the machine. However, the construction is such as to admit of the ready detachment of the guide should it be preferred to remove the same for any reason. 95

When the guide is in position the paper 8 is fed to the machine in the usual way by being introduced between the shelf or table 2 and the upper enlarged or recurved end 7 of the guide and, as the paper passes around the platen 1, it engages the lower portion of the guide 5 and is directed upwardly and rearwardly and prevented from passing around the platen a second time which is a source of trouble and the objectionable 100 feature overcome by the invention.

In the modification shown in Figure 4 the member 5^a has its lower end deflected, as indicated at 9 to engage the upper side of the rod 3 and the recurved portion 7^a extended, as indicated at 10, to project beyond the lower end of the member 5^a and termi-

nating in a hook 11 which is adapted to engage about the rod 3 and overlap the lower end of the member 5^a. The parts 9 and 11 constitute elements of a clasp, the rod 3 being received in the bight of the hook 11 and the deflected end 9 engaging over the rod 3 and serving to retain the device in position as will be readily appreciated.

It will be readily understood that the 10 paper guide may be cheaply manufactured in quantity and supplied at a nominal cost and may be finished in any preferred way. While metal is preferred, nevertheless, any suitable sheet material may be employed in 15 the manufacture of the article.

Having thus described the invention, I claim:

1. As a new article of manufacture, a 20 paper guide for typewriting machines to prevent the paper being carried around the platen a second time, the same consisting

of a guide member having a clasp at its lower end to engage the pressure roller rod, and having its upper end re-curved to provide a rest to engage the paper shelf, both 25 the clasp and the rest projecting from the same side of the guide which is straight and flat upon its top side.

2. In combination with a typewriting machine, embodying a platen, a paper shelf and a rod paralleling the platen and supported at its ends by the frame, a paper guide consisting of a member having a clasp at one end to engage the said rod and having its opposite end recurved to engage the paper 35 passing over the paper shelf to the platen and supporting the paper passing from the platen out of possible contact with the paper passing to the platen.

In testimony whereof I affix my signature.

VINCENT GAGE. [L. S.]
